(57) **CLAIM**

The ornamental design for a stick-type glue dispenser, as shown and described.

DESCRIPTION

FIG. 1 is a perspective view of a stick-type glue dispenser showing my new design;

FIG. 2 is a front elevation view thereof. A rear elevation view is a mirror image of FIG. 2;

FIG. 3 is a left side elevation view thereof. A right side elevation view is a mirror image of FIG. 3;

FIG. 4 is a top plan view thereof; and,

FIG. 5 is a bottom plan view thereof.
